UNITED STATES PATENT OFFICE.

GERHARD STEIN, OF NEUSORNEWITZ, NEAR MEISSEN, GERMANY.

POT FOR GLASS-MELTING FURNACES.

Application filed June 24, 1926, Serial No. 118,256, and in Germany June 25, 1925.

For a more efficient use of the heating-gases for the pots of glass-melting-furnaces it is known to arrange grooves or passages within the bottom of the pots. The ends of 5 said grooves or passages are closed in this known construction so that the heating or fire-gases are retained and cannot freely pass through said passages and thereby a complete profit from the heating-gases is not 10 ensured in spite of the increased bottom-surface.

Now, according to the present invention a complete use of the heating or fire-gases touching the bottom of the pot is obtained 15 or ensured by arranging open grooves or passages on the under surface of the bottom of the pot, said grooves or passages running parallel with each other or crosswise from edge to the opposite edge in such a 20 manner that the heating or fire-gases are drawn through said open grooves or passages and the heat is supplied to the bottom of the pot in permanently fresh quantities.

25 The object of the invention is represented in the drawing annexed to the description in two forms of construction.

Fig. 1 represents in a vertical section and Fig. 2 in a view from the bottom the first 30 form of construction.

Fig. 3 represents in a view from the bottom the second form of construction in which the grooves or passages arranged in the bottom run crosswise.

35 As shown in Figs. 1 and 2, open grooves or passages *b* arranged in the bottom *a* of the melting-pot run from edge to the opposite edge of the pot in such a manner that

the bottom-surface is increased on the one hand and a better passage of the fire-gases 40 on the bottom is ensured, on the other hand, so that the heat is supplied to the bottom in permanently fresh quantities within the grooves or passages.

In the form of construction represented 45 by Fig. 3 the grooves or passages *b* are arranged crosswise, so that the underside of the bottom is provided with downwardly projecting parts *c*. This form of construction has the advantage that a better passage 50 of the fire-gases at the bottom *a* or within the passages *b* is ensured in any suitable position of the pot containing molten glass.

What I claim is:

1. Pot for glass-melting furnaces which 55 consists in that the underside of the bottom is arranged with open grooves or passages running adjacent one another from one edge to the opposite edge of the pot.

2. Pot for glass-melting furnaces which 60 consists in that the underside of the bottom is arranged with open grooves or passages running parallel from edge to the opposite edge of the pot.

3. Pot for glass-melting furnaces which 65 consists in that the underside of the bottom is arranged with two series of open grooves or passages running adjacent one another from one edge to the opposite edge of the pot, one series of open grooves being disposed substantially at right angles to and crossing the other series of grooves.

In testimony, that I claim the foregoing as my invention, I have signed my name this 9th day of June, 1926.

GERHARD STEIN.
